F. M. KNOLL

TOY FIRE ALARM BOX

Filed May 9, 1924

Frederick M. Knoll,

INVENTOR

BY
Robert B. Killgore
ATTORNEY

UNITED STATES PATENT OFFICE.

FREDERICK M. KNOLL, OF BROOKLYN, NEW YORK, ASSIGNOR TO THE VIKING TOOL & MACHINE CO., INC., OF BROOKLYN, NEW YORK, A CORPORATION OF NEW YORK.

DESIGN FOR A TOY FIRE-ALARM BOX.

Application filed May 9, 1924. Serial No. 9,526. Term of patent 7 years.

To all whom it may concern:

Be it known that I, FREDERICK M. KNOLL, a citizen of the United States, residing at the borough of Brooklyn, New York city, county of Kings, and State of New York, have invented a new, original, and ornamental Design for Toy Fire-Alarm Boxes, of which the following is a specification, reference being had to the accompanying drawing, forming a part hereof.

The figure is a perspective view of a toy fire alarm box showing my new design.

I claim:—

The ornamental design for a toy fire alarm box, as shown.

FREDERICK M. KNOLL.
